UNITED STATES PATENT OFFICE.

ARTHUR L. BETTS, OF CINCINNATI, OHIO, ASSIGNOR TO AUGUSTINE DAVIS, JR., OF COVINGTON, KENTUCKY.

VALVE-CONTROL MECHANISM FOR TANKS.

Application filed August 11, 1921. Serial No. 491,638.

To all whom it may concern:

Be it known that I, ARTHUR L. BETTS, a citizen of the United States, and resident of Cincinnati, in the county of Hamilton 5 and State of Ohio, have invented certain new and useful Improvements in Valve-Control Mechanism for Tanks, of which the following is a specification.

This invention relates to valve control mechanism for tanks, more especially for vehicle tanks or tank-wagons. Specifically, the invention comprises improvements in the mechanism for controlling the emergency valves of oil-tank wagons disclosed 15 in the Davis and Betts application Serial No. 381,575, filed May 15, 1920, though it is not necessarily limited to that specific mechanism.

In the accompanying drawings forming a 20 part hereof:

Fig. 1 is a side elevation of a compartmented tank-wagon tank and its bucket-box and valve mechanism, embodying the invention, a portion of the wall of the bucket-box being broken away in order that parts within may be indicated, the mechanism being shown in the open condition;

Fig. 2 is a side elevation on a larger scale of the tank and the bucket-box, with wall 30 portions broken away and parts within shown partly in section and partly in elevation, the mechanism being represented in the closed condition;

Fig. 3 is a fragmentary plan view showing parts within and above the bucket-box, the upper part of said box being cut away and its door being seen in section, two positions of the mechanism being represented by full and broken lines;

Fig. 4 is a vertical longitudinal section 40 through the fluid-check device;

Fig. 5 is a fragmentary side elevation of the compound control rod with its locking device;

Fig. 6 is a front end elevation of the same; and

Fig. 7 is a view at the region of the lock showing the casing in longitudinal section and the inner rod in elevation, and showing 50 the locking bolt turned to the releasing position, and the casing starting to move forward under the action of the valve-closing springs.

The tank 1 illustrated in Fig. 1 has compartments 2, 3, and a bucket-box 4 at the

rear end, the whole constructed and supported upon the chassis or mounting of the vehicle in an approved manner. The bucket-box has a rear door 5, which may be of the top-hinged variety, as indicated in Fig. 1, wherein the door is represented as being open and the operating handle 6 pulled out to open the emergency valves 7 commanding the bottom outlets 8 of the tank compartments. From said outlets 65 pipes 9 extend rearward beneath the tank and bucket-box and terminate in the usual delivery faucets 10 at the rear of the vehicle. The emergency valves are contained in the lower portions of the compartments 70 and are preferably of the construction covered by the Davis and Betts Patent No. 1,284,063, granted November 5, 1918. They are unseated by pulling them upward and closed downwardly by the action of springs 75 11, which are preferably incorporated in the valve structures.

Operating connections, marked generally 12, pass upward from the emergency valves through stuffing-boxes 13 in the top of the tank, above which their guided rod portions 80 14 connect with bell-cranks 15 in brackets 16. The depending arms of these bell-cranks engage and support pivotally fittings 17 on a control rod 18, which extends longitudinally over the top of the tank and therewith joined bucket-box. The rear end of said control rod is pivotally connected to a crank 19 on the upper end of a vertical 85 rock-shaft 20, which passes through the top 90 of the bucket-box and is supported therein and by a bracket 21 bolted to a shelf 22. To the lower end of the rock-shaft 20, below said bracket, is pinned the handle lever 6, which in the closed condition of the emergency valves lies at the inner side of the 95 closed door 5 in the manner shown in Fig. 3.

In order to unseat the emergency valves to permit the oil to pass to the rear faucets, the operator opens the door of the bucket-box, and, grasping the handle portion of the lever, which is broken off in Fig. 3, pulls the lever outwardly of the door-opening. In this position the lever and the remainder of the valve mechanism are held against the action of the springs 11 tending to close the valves, by a catch 23, which preferably comprises a bottom block or flange 24 carried by the bracket 21 and presenting a holding shoulder 25 with which cooperates a tail 100 105 110

piece 26 of the handle lever, the pin 27 connecting the lever to the rock-shaft permitting the lever to be tilted so as to move said tail piece vertically into and out of engagement with said shoulder. When the tail piece is caught behind the shoulder, the handle lever is held projecting outwardly through the door-opening in the position indicated by broken lines in Fig. 3. An interlock is thus constituted between the valve mechanism and the bucket-box door, whereby the door is open when the emergency valves are open and whereby the valves must be closed when the door is closed. To effect closing of the valves, the operator raises the weight of the lever 6, so as to carry the tail piece 26 down below the shoulder 25, whereupon the valve springs 11 act upon the mechanism to close the valves and to swing the handle into the box, clearing the door 5, which can then be closed and locked. In these respects the mechanism illustrated is substantially like that of the Davis and Betts application Serial No. 381,575 aforesaid.

In order to save the mechanism and the valve and valve seats from the impact of closing under the action of the springs, I provide a fluid-check 28 connected with the control mechanism. This device is most advantageously connected with the portion of the vertical rock-shaft 20 within the bucket-box. In the preferred embodiment it comprises a horizontal cylinder pressed on a block 29 which contains a duct and adjustable needle valve 30 for controlling the escape of air, the block being pivot-bolted at 31 to the shelf 22. A spider 32 clamped to the open end of the cylinder constitutes a guide for the rod 33 of the piston 34. The end of this rod is pivoted at 35 to the crank arm 36 on the rock-shaft above the operating handle 6. The piston itself is so constructed, in a manner familiar in tire pumps, as to provide for a rapid inlet of air during the outward movement of the piston, whereas upon inward movement, produced by closing of the valves, the air is trapped and compressed between the piston and the block 29, being allowed to escape only at the rate permitted by the adjustment of the needle valve 30.

The control-rod 18, instead of being a single rod, is a compound rod comprising relatively movable members normally locked or operatively connected together for the operations which have been described and capable of being unlocked or released one from the other so as to cause the emergency valves to close without releasing the operating and holding means in the bucket-box. To this end the said rod is composed of a tubular casing 37 and an inner rod 38, which latter projects rearward beyond the casing 37 and is the member which is connected to the

rock-shaft 20 and by the latter to the mechanism in the bucket-box. The outer sleeve or casing 37, on the other hand, bears the clamps or fittings 17, to which are connected the bell-cranks 15, which in turn are connected with the emergency valves 7. The releasable lock between the members of the compound control rod is preferably located at the forward end of the latter, and in the preferred and simple embodiment comprises a turnable locking member or bolt 39 journaled in openings in the sides of a cap piece 40 on the casing and cooperating with a notched region 41 of the inner rod which affords a holding shoulder 42. This bolt consists of a piece of round rod disposed transversely of the control rod and slabbed off or cut away at 43 between its journal regions, one end portion of the bolt being bent to form a crank 44. In the locking condition the slabbed portion of the bolt is tilted so that its corner portion 45 is in holding engagement with the shoulder 42. In this position it is held against accidental displacement by a spring 46, one end of which bears upon the cap piece 40 and the other end upon the bolt, the turning of the bolt under the action of this spring being limited by the contact of the corner region 45 with the bottom of the recess in the inner rod 38. In this manner the two parts of the compound control rod are reliably locked against relative movement under the pull of the valve springs 11 in the one direction and the pull of the operating handle 6 in the other direction. A comparatively slight force applied to the crank 44, however, is sufficient to turn the bolt through a fractional revolution, so that the holding corner 45 is withdrawn from the shoulder 42, the cut-out portion of the bolt then permitting the outer casing 37 to jump forward under the action of the valve springs, the valves thus being permitted to close through the movement of the outer casing while the inner rod 38 and the mechanism connected therewith remain stationary.

This operation may be conveniently effected by the driver from the cab of the vehicle by means of a flexible cable 47 connected to the crank 44 extending to the front of the tank and having a suitable handle 48.

Broadly, it will be seen, I provide a control means for the spring-closing valves comprising two parts which are relatively movable but normally operatively connected, one of the parts having operative connection with the valves and the other part being related to the main operating and holding means, together with an auxiliary releasing device comprising a bolt or other member interposed between the parts and movable to release one of them from the other when the valves are standing open.

While a preferred form of the invention has been described in detail, I do not wish to be limited to the specific embodiment illustrated, since numerous changes and substitutions of equivalents may be made.

5 I claim:

1. In combination with a vehicle tank having an outlet, an automatically closing valve commanding said outlet, a control rod 10 passing lengthwise of the tank, a connection between said control rod and said valve, operating and holding means connected with the rear end of the control rod, a releasable lock in the control rod, and means connected 15 with the forward end of the control rod to release said lock to permit the valve to close independent of the means at the rear end.
2. In a tank vehicle, the combination with a tank body comprising a series of compartments each having an outlet, automatically closing valves for said outlets, a control rod 20 passing lengthwise of the tank body and branch connections from said control rod to the several valves, operating and holding 25 means connected with the rear end of the control rod, a releasable lock in the control rod, and means connected with the forward end of the control rod to release said lock to permit the valves to close independent of the 30 means at the rear end.

3. In combination with a tank having an outlet, a valve cooperative with said outlet,

a compound control rod comprising a casing and an inner rod, a connection between the casing and the valve, suitable operating 35 and holding means cooperative with the inner rod at one end of the compound control rod, and a manually releasable lock between the casing and inner rod toward the 40 other end of the control rod.

4. In combination with a vehicle tank having a bottom outlet, a valve cooperative with said outlet, a compound control rod extending longitudinally over the top of the tank 45 and comprising a casing and an inner rod, a connection passing downward from the casing to the valve, suitable operating and holding means at the rear end of the tank connected with the inner rod, and a lock between the rod and casing adapted for manual release at the forward end of the tank.

5. In a vehicle tank having a bottom outlet, and spring-urged mechanism for said outlet, an operating connection passing from the valve through the top of the tank, a 55 longitudinal control rod connected therewith, a bucket-box, a vertical rock-shaft passing through the top of the bucket-box and connected with said control rod, operating and holding means in the bucket-box co-operative with said rock-shaft, and a fluid-check also connected with said rock-shaft. 60

ARTHUR L. BETTS.
